UNITED STATES PATENT OFFICE

PHILLIP R. ANDREWS, OF SEATTLE, WASHINGTON, ASSIGNOR TO PACIFIC MARINE SUPPLY COMPANY, OF SEATTLE, WASHINGTON, A CORPORATION OF WASHINGTON

MARINE LIGHT

Application filed December 16, 1929. Serial No. 414,328.

My present invention relates to the art of lights and more particularly that type of light that is used as a signal or marker and which finds its most common use in the marine field. The marine laws require lights on certain classes of marine obstructions, such as wharves, fish traps and the like. It often becomes quite a problem for the individual to maintain a light on such structures as fish traps during the long periods that there is no attendant present.

It is the purpose of my invention to provide a light which will maintain a signal for long periods, often as much as 30 or 40 days, and which will need no attention during this period. It is also desirable to have a light of this character that can be made cheaply and is not affected by climatic conditions.

Therefore, the principal object of my invention is to provide a signal light that will give the maximum beam of light with an expenditure of very little energy.

A further object is to provide a signal light that will operate without attention for long periods of time.

A further object is to provide a signal light whose design lends it to economical construction.

Other and more specific objects will be apparent from the following description taken in connection with the accompanying drawings, wherein Figure 1 is a cross-sectional view through the preferred form of my light showing the battery compartment opened.

Figure 2 is a fragmentary cross-sectional view showing part of the structure of Figure 1 but with an alternate lighting system.

Figure 3 is a view of the light circuit of the modified form partly in elevation and partly diagrammatical.

Referring to the drawings, throughout which like reference numerals indicate like parts, numeral 4 designates a tubular lens which when of the type shown, is normally called a "Fresnel" light.

Located at the center of the lens is the light globe 6, which is normally of low candle power and is adapted to be lighted by current supplied by a number of dry cell bat-

teries connected in parallel. The light is held in any convenient insulated fitting as 8, which in turn is supported by the member 10 which is adapted to screw into the apex of the conical reflector 12. I have found it very desirable to use a structure similar to that shown wherein the light may be removed for inspection or replacement without disturbing the reflector 12. The reflector 12 may be of any desirable construction. I have

found plated metal most satisfactory as it is not subject to breakage. This is held in place by a plurality of supporting brackets 14. Disposed immediately above light 6 is a second conical reflector 16. This reflector is similar to reflector 12 except that no provision is made for a light and the tip is rounded off as at 18. Any convenient means may be employed to maintain reflector 16 in position. I have found, however, that the

spring cylinder arrangement shown is very convenient. This consists of a tubular member 20, which is secured to reflector 16 and of such size as to slide easily within the tube 22, which is secured to the upper dome member 24. A coil spring 26 in compression presses the reflector snugly down on the lens 4. The light may be supported in any convenient manner as by the lunette 28 which is secured to the dome 24. Member 24 is usually

spun with an outwardly extending ledge 30 and a downwardly extending portion 32, which is adapted to engage the lens at 34. Lens 4 is supported at its lower extremity by the base member 36, which has an inwardly extending portion 38 and an outwardly extending ledge 40. Member 38 engages the lower portion of the lens at 42, holding it in position.

Members 24 and 36 are joined together by a plurality of tie rods 44, which also serve, along with the horizontally disposed rings 46, to act as a shield or guard for the lens 4.

A battery compartment is provided, which is intended to normally house a number of dry cell batteries, although I believe it will be apparent that any form of battery might be used, or even a fluid-lamp might be substituted for the entire electrical system.

The battery compartment 50 is provided

with a male portion 52, of such dimension as will fit inside of member 36. This is desirable as it prevents water entering the battery compartment. I have found that the 5 hinge members 54 co-acting with the tongue members 57, provide a very satisfactory method of securing the battery compartment to the light proper.

In Figure 2, I have shown a slight modification of my device. This is to meet the demands of certain regulations that require an alternate light as a safety precaution. In this form all elements of my light are used excepting reflector 16 which is dispensed with, 10 and a second reflector of the form of reflector 12 is used in an inverted position. In this form neither of the lights 6 or 56 are normally in the exact optical center of the lens, although they can easily be on the axis 15 of the lens. It will be apparent I believe, that these two lights might be connected in parallel so that they will both burn all the time. This feature, while used under certain conditions, has the disadvantage of using 20 twice the electrical current and also that in case one light burns out, the intensity of the light is diminished by one-half. To overcome this fault I have provided the electromagnetic device shown as 59 in Figure 3, 25 wherein 60 represents a suitable current supply, one side of which is connected to both lights by the wires 62 and 64. The other side goes to a binding post 65, which is provided with a pivot 66 and a contact member 67. 30 Light 6 has its other terminal connected to binding post 69 and light 56 has its other terminal connected to binding post 70.

I believe it will be apparent that if the bar 67 is manually placed in engagement 40 with contact 72, current will flow from the battery through light 56, the binding post 70 and the electromagnet 74. Inasmuch as 45 67 is of magnetic material, this circuit will remain complete until light 56 is either removed or burns out. When this occurs spring 76 operates to move bar 67 until it engages the base of binding post 69. This then forms a circuit through light 6 to the battery.

What I claim is:

50 1. A signal light consisting of a tubular lens; a dome member; a base member; means adapted to secure the dome and the base members in spaced relationship; said dome member having a downwardly extending portion terminating in a cylindrical rim of reduced diameter providing a circular opening adapted to receive one end of the tubular lens; said base member having an upwardly extending portion terminating in a cylindrical rim of reduced diameter providing an opening adapted to receive the opposite end of said tubular lens; an upwardly extending conical reflector disposed above the first named reflector and pointing in the opposite direction 55 with said tubular lens, a second conical reflector disposed above the first named

reflector and pointing in the opposite direction therefrom adapted to rest upon the top surface of said tubular lens; an electric light disposed at the optical center of said tubular lens; a removable battery compartment 70 adapted to be secured to the base member, and a plurality of batteries in said battery compartment adapted to supply electrical energy to said electric light.

2. A signal light consisting of a tubular lens; a dome member; a base member; means adapted to secure the dome and base members in spaced relationship; said dome member having a downwardly extending portion terminating in a cylindrical rim of reduced diameter providing a circular opening adapted to receive one end of the tubular lens; said base member having an upwardly extending portion terminating in a cylindrical rim of reduced diameter providing an opening 80 adapted to receive the opposite end of said tubular lens; a plurality of brackets secured to said base member and adapted to support said lens; an upwardly extending conical reflector positioned concentrically with said tubular lens and arranged to be supported by said brackets; a second conical reflector disposed above the first named reflector and pointing in the opposite direction therefrom 85 adapted to rest upon the top surface of said tubular lens; an electric light disposed at the optical center of said tubular lens; a removable battery compartment adapted to be secured to the base member; and a plurality 90 of batteries in said battery compartment 95 adapted to supply electrical energy to said electric light.

3. A signal light consisting of a tubular lens; a dome member; a base member; means adapted to secure the dome and base members in spaced relationship; said dome member being provided with a circular opening adapted to receive one end of the tubular lens; said base member having an opening adapted to receive the opposite end of said tubular lens; a plurality of brackets secured to said base member and adapted to support said lens; an upwardly extending conical reflector positioned concentrically with 100 said tubular lens and arranged to be supported by said brackets; a second conical reflector disposed above the first named reflector and pointing in the opposite direction therefrom adapted to rest upon the top surface of said tubular lens; a tubular member 105 secured to said upper reflector; a tubular guide member secured to said dome member and adapted to engage the first named tubular member in sliding relationship; resilient means disposed within said tubular guide 110 member adapted to urge said upper reflector downwardly and thus secure the tubular lens positively in position; an electric light disposed at the optical center of said tubular lens; a removable battery compartment adapted 115 120 125 130

to be secured to the base member; and a plurality of batteries in said battery compartment adapted to supply electrical energy to said electric light.

5 4. A signal light consisting of a tubular lens; a dome member; a base member; means adapted to secure the dome and base members in spaced relationship; said dome member being provided with a circular opening adapted to receive one end of the tubular lens; said base member having an opening adapted to receive the opposite end of said tubular lens; a plurality of brackets secured to said base member and adapted to support 10 said lens; an upwardly extending conical reflector positioned concentrically with said tubular lens and arranged to be supported by said brackets; a second conical reflector disposed above the first named reflector and 15 pointing in the opposite direction therefrom adapted to rest upon the top surface of said tubular lens a tubular member secured to said upper reflector; a tubular guide member secured to said dome member and 20 adapted to engage the first named tubular member in sliding relationship; resilient means disposed within said tubular guide adapted to urge said upper reflector downwardly and thus secure the tubular lens positively in position; an electric light disposed 25 at the optical center of said tubular lens; a removable battery compartment adapted to be secured to the base member and to fit within the said base member so that water will 30 not drain into said battery compartment; tongue members secured to said base member; hinge members secured to said battery compartment in fixed operating relationship with said base members and a plurality of 35 batteries in said battery compartment adapted to supply electrical energy to said electric light.

In witness whereof, I hereunto subscribe my name this 27th day of November A. D. 40 1929.

PHILLIP R. ANDREWS.
